OSCILLATING FAN.

1,394,975.

Specification of Letters Patent.

Patented Oct. 25, 1921.

Application filed March 9, 1920. Serial No. 364,422.

To all whom it may concern:

Be it known that I, PHILIPPE DE CLAMECY, a citizen of the United States, residing at Boston, in the county of Suffolk and State 5 of Massachusetts, have invented certain new and useful Improvements in Oscillating Fans; and I do hereby declare the following to be a full, clear, and exact description of the invention, such as will enable others 10 skilled in the art to which it appertains to make and use the same.

This invention relates to oscillating fans and more particularly to fans which are oscillated by the action of air currents produced by the rotation of the fan blades upon current obstructing means carried by the oscillating element of the fan and operated to alternately obstruct the delivery of air at opposite sides of the axis of oscillation.

One object of the present invention is to provide a fan of the general character above indicated in which the current obstructing means is rendered operative to effect the reversal of the direction of oscillation of the fan solely by the action of air currents produced by the fan.

To this end a feature of the invention comprises the provision, in an oscillating fan, of a current obstructing device supported by the oscillating element of the fan, said device being free to rotate continuously in the same direction about the axis of rotation of the fan wheel and presenting to the air blast a face which is inclined to the plane of rotation of the fan blades.

Other objects of the invention and the features of construction by which they are attained will be set forth hereinafter in connection with the following description of what is now considered to be the preferred embodiment of the invention illustrated in the accompanying drawings, in which:—

Figure 1 is a view in front elevation of the fan; Fig. 2 is a view in side elevation thereof, a portion being broken away to disclose parts of the fan otherwise obscured; and Fig. 3 is a detail sectional view, on an enlarged scale, showing the current obstructing device, the section being taken on the line 3—3 of Fig. 1.

As illustrated in the drawings, an electric motor 4 having a rotary fan wheel 5 secured to its armature shaft, is pivotally mounted

upon a post 6 which is journaled to oscillate freely in a hollow pedestal 7 rising from a stationary base 8. The pivotal connection between the motor 4 and the post 6, which permits tilting adjustment of the motor and fan to vary the path swept by the air blast of the fan, comprises a bolt 9 that extends transversely through the top of the post and through a pair of tongues 10 depending from the motor casing and embracing the post. The pivot bolt 9 is provided with a thumb-screw 11 by means of which the tongues 10 are clamped to the post to hold the motor in its angularly adjusted position. The post 6 may be supported, as shown, upon ball-bearings 12 and it may be made hollow to permit the passage therethrough of the wires leading from the motor. The fan wheel 5 is inclosed and protected from contact with exterior objects by the usual cage or guard frame 14 which is rigidly attached to the motor casing.

In order to attain a greater range of tilting adjustment of the motor and fan than that permitted by the pivotal connection between the motor and the post 6, provision is made for universal angular adjustment of the pedestal 7 and the base 8. To this end the pedestal and base are connected by means of a ball-and-socket joint, disclosed in a co-pending application Serial No. 359,998, filed February 19, 1920, by the present applicant and assigned to the B. F. Sturtevant Company. For the purpose of insuring that the fan will be easily oscillated by the action of its own air blast upon a current obstructing device, irrespective of whether the post 6 and pedestal 7 are supported in vertical or tilted positions, the motor 4 is so disposed with respect to the post 6 that the motor and all parts carried thereby are perfectly balanced on opposite sides of the axis of oscillation of the fan.

The current obstructing device, against which the air blast of the fan is directed to cause the fan to oscillate as it rotates, comprises a disk 15 which is laterally curved or flexed into the form of a propeller blade and which is mounted in front of the fan wheel for rotation about the axis of the latter. To this end the disk 15 is carried by a supporting arm 16, radially projecting from a bearing sleeve 17, which is journaled on a stud 18 that is carried by the cage or guard frame

14 and is disposed co-axially with the armature shaft of the motor. The stud 18 is removably secured to a hub 19 (Fig. 4) from which the guard frame wires radiate, the 5 stud having at one end a reduced threaded portion which projects through a central opening in the hub 19 and which is provided with a nut 20 that is tightened against the outer face of the hub. The bearing sleeve 10 17 is confined and free to turn between a head 21, at the inner end of the stud 18, and a spacing collar 22 that is interposed between the sleeve and the hub 19 of the guard frame.

15 The current obstructing disk 15 is of such form and is so disposed, with its face inclined to the plane of rotation of the fan wheel, that the blast of air produced by the fan will tend to rotate the disk about 20 the stud 18. In order to facilitate the rotation of the obstructing disk 15, the weight of the disk, the supporting arm 16, and certain other associated parts, shortly to be described, are exactly balanced by a counter- 25 balance weight 23 that is carried by a weight arm 24 radially projecting from the bearing sleeve 17 on the opposite side of the stud 18 from the disk-supporting arm 16.

In the construction shown, the obstructing disk 15 is stiffened and maintained in 30 its laterally flexed condition by means of a flat reinforcing disk 25 having laterally projecting from its periphery a segmental flange 26. The flat reinforcing disk 25 is 35 disposed in a plane parallel to the plane of rotation of the fan wheel. The edge of the flange 26 rises gradually from each of its ends, which lie in the plane of the disk 25, to the middle point of said edge, and one 40 side of the curved obstructing disk 15 is secured adjacent its periphery to this edge of the flange 26 and to the marginal portion of the disk 25 which intervenes between the ends of said flange.

45 In order to transmit the thrust of the obstructing disk to the peripheral portions of the guard frame 14 so as to readily effect the oscillation of the motor and fan, a spherical roller 27 is journaled on a pin 28 50 projecting radially from the flange 26 of the supporting frame for the obstructing disk, and arranged to roll over an annular track 29 which is supported by the guard frame 14. The track 29 consists of a flat 55 ring which is suitably secured to the wires of the guard frame so that it is rigidly supported in a plane parallel to the plane of rotation of the fan wheel with its peripheries concentric with the path of rotation 60 of the roller 27. With this construction, the bearing stud 18, about which the obstructing disk rotates, is relieved of the thrust of said disk, and the obstructing disk itself is prevented from being laterally displaced by the 65 force of the air blast from the fan.

The obstructing device is a novel and distinctive feature of the present invention which is certain to attract attention as it slowly and continuously rotates in front of the fan wheel and accordingly it offers an 70 excellent opportunity for an effective advertising display such, for example, as the name of the manufacturer of the fan or an appropriate name-plate or trademark. In order that any legend or display which it 75 may be desired to associate with the obstructing device shall be constantly maintained in an upright position so that the display will be readable or properly presented to view at all times, provision is 80 made for preventing the display matter from being turned relatively to the axis of the fan as the obstructing device rotates. To this end a separate disk 30 is provided to carry the legend or display, and this disk 30 85 is centrally pivoted by a pin 31 to the front of the reinforcing disk 25 and the display disk 30 is provided with a weight or thickened portion 32 which causes the former to rotate freely about its pivot 31, as it travels 90 bodily with the obstructing member about the stud 18, so that its thickened portion 32 is maintained lowermost by gravity.

While the particulars of construction herein set forth are well suited to one form 95 of the invention, it is to be understood that these particulars are not essential since they may be variously changed or modified without departing from the true scope of the actual invention as defined by the following 100 claims.

Having described the invention, what is claimed as new is:—

1. An oscillating fan having, in combination, a motor, a fan wheel, a support upon 105 which the motor and fan wheel are arranged to oscillate, a current obstructing device adapted to be rotated about the axis of the fan wheel to cause the fan to oscillate alternately in opposite directions as it rotates, a 110 guard frame carried by the motor and enclosing the fan wheel, a track supported by the guard frame, and a bearing member carried by the current obstructing device for engaging with the track as said device ro- 115 tates.

2. An oscillating fan having, in combination, a motor, a fan wheel, a support upon 120 which the motor and fan wheel are arranged to oscillate, and a current obstructing device adapted to be rotated continuously about the axis of the fan wheel to cause the fan to oscillate alternately in opposite directions as it rotates.

3. An oscillating fan having, in combination, a motor, a fan wheel, a support upon 125 which the motor and fan wheel are arranged to oscillate, and a current obstructing device adapted to be rotated continuously about the axis of the fan wheel by the action of 130

- the current of air produced by the fan to cause the fan to oscillate alternately in opposite directions as it rotates.
4. An oscillating fan having, in combination, a motor, a fan wheel, a support on which the motor and fan wheel are mounted to oscillate, the support comprising a base and a pedestal connected therewith with provision for angular adjustment relatively thereto, the motor being so disposed relatively to the support that the weight of the motor and fan is balanced on opposite sides of the axis of oscillation of the fan, and a current obstructing device adapted to be rotated continuously about the axis of the fan wheel by the action of the current of air produced by the fan to cause the fan to oscillate alternately in opposite directions as it rotates.
5. An oscillating fan having, in combination, a motor, a fan wheel, a support on which the motor and fan wheel are arranged to oscillate, and a current obstructing device supported by the oscillating element of the fan, said device being free to rotate continuously about the axis of the fan wheel and presenting to the current of air produced by the fan wheel a face inclined to the plane of rotation of the latter whereby the action of said current effects the rotation of said member.
6. An oscillating fan having, in combination, a motor, a fan wheel, a support on which the motor and fan wheel are arranged to oscillate, a current obstructing device pivotally mounted for balanced rotation about the axis of the fan wheel and presenting an inclined face to the current of air produced by the fan whereby the obstructing member is caused to rotate continuously and the fan wheel to oscillate alternately in opposite directions during the rotation of the latter.
7. An oscillating fan having, in combination, a motor, a fan wheel, a guard frame carried by the motor and inclosing the fan wheel, a support on which the motor and fan wheel are arranged to oscillate, and a current obstructing device for causing the fan to oscillate alternately in opposite directions as it rotates, said device comprising a disk mounted to present an inclined face to the current produced by the fan at one side of the axis of rotation of the latter, a support for said disk, a bearing stud carried by the guard frame and arranged coaxially with the armature shaft of the motor on which the disk support is mounted to rotate, a counter weight for balancing the weight of said disk and disk support, an annular track carried by the guard frame, and a roller carried by the obstructing device and bearing against said track to transmit thereto the thrust of the obstructing device.
8. An oscillating fan having, in combination, a motor, a fan wheel, a stationary support on which the motor and fan wheel are arranged to oscillate, a current obstructing device supported by the oscillating element of the fan and adapted to be rotated continuously about the axis of the fan wheel by the action of the current of air produced by the fan to cause the fan to oscillate alternately in opposite directions as it rotates, and a display member pivoted above its center of gravity to said obstructing device to cause it to rotate about its pivotal connection with the obstructing device as the latter rotates about the axis of the fan wheel so as to prevent the display member from being turned relatively to the stationary fan support during said rotation of the obstructing member.
9. An oscillating fan having, in combination, a motor, a fan wheel, a stationary support on which the motor and fan wheel are arranged to oscillate, a current obstructing disk supported by the oscillating element of the fan and adapted to be rotated continuously about the axis of the fan wheel by the action of the current of air produced by the fan to cause the fan to oscillate alternately in opposite directions as it rotates, a display disk disposed in a plane substantially normal to the axis of the fan wheel and centrally pivoted to the obstructing disk, and a weight secured to said display disk adjacent its periphery to cause the latter to rotate about its pivotal connection with the obstructing device as the obstructing device rotates about the axis of the fan wheel so as to maintain the display disk against turning relatively to the stationary fan support during said rotation of the obstructing disk.
10. An oscillating fan having, in combination, a motor, a fan wheel, a stationary support on which the motor and fan wheel are arranged to oscillate, a current obstructing device supported by the oscillating element of the fan and adapted to be rotated continuously about the axis of the fan wheel by the action of the current of air produced by the fan, said device presenting an inclined face to said current of air and having an oppositely directed display face disposed in a plane normal to the axis of the fan wheel.
11. An oscillating fan having, in combination, a motor, a fan wheel, a support on which the motor and fan wheel are arranged to oscillate, a current obstructing device supported by the oscillating element of the fan, said device being arranged to rotate about the axis of the fan wheel and presenting to the current of air produced by the fan wheel a face inclined to the plane of rotation of the latter, and means for transmitting the thrust of said member to the outer portions of said oscillating element.
